PLAYGROUND CLIMBER OR SIMILAR ARTICLE

Robert S. Wormser, Hillsdale, Mich., assignor to Game Time, Inc., Litchfield, Mich., a corporation of Michigan

Filed Dec. 30, 1968, Ser. No. 15,140

Term of patent 14 years

Int. Cl. D21—04

U.S. Cl. D34—5

FIG. 1

FIG. 2

FIG. 3

FIG. 4

FIG. 1 is a side, elevational view of my new design for a playground climber or similar article as looking through the side access openings, the opposite side being identical thereto,

FIG. 2 is a side, elevational view of my new design as taken from the right of FIG. 1, the opposite side thereof being identical thereto,

FIG. 3 is a top plan view of my new design, and

FIG. 4 is a bottom view of the design of the invention.

I claim:

The ornamental design for a playground climber or similar article, substantially as shown and described.
